DESIGN FOR A PENCIL

Willy Koerper, Nuremberg, Germany

Application June 14, 1935, Serial No. 57,273
In Germany April, 1935

Term of patent 7 years

To all whom it may concern:

Be it known that I, Willy Koerper, a citizen of the German State, residing at Nuremberg, Germany, have invented a new, original, and ornamental Design for a Pencil, of which the following is a specification, reference being had to the accompanying drawing, forming part thereof.

The figure is a perspective view of a pencil showing my design.

The pencil is of blue color and has longitudinal stripes in black color, near the rear end of the

pencil two double rings in gold and stamped at a distance apart, and lyres are stamped in gold in the space between the two double gold rings, a ring of other color than gold or blue, produced by dipping, on the portion of the sheath between the rear stamped double gold ring and the rear end of the sheath, all as shown on the drawing.

I claim:

The ornamental design for a pencil, as shown and described.

WILLY KOERPER.
